UNITED STATES PATENT OFFICE.

WILLIAM F. AIDLOTTE, OF HIATTVILLE, KANSAS, ASSIGNOR OF ONE-HALF TO EARL WILLIAMS, OF HIATTVILLE, KANSAS.

SICKLE-BAR.

1,233,950.

Specification of Letters Patent. Patented July 17, 1917.

Application filed October 13, 1916. Serial No. 125,390.

To all whom it may concern:

Be it known that I, WILLIAM F. AIDLOTTE, a citizen of the United States, residing at Hiattville, in the county of Bourbon, State 5 of Kansas, have invented certain new and useful Improvements in Sickle-Bars, of which the following is a full and exact specification.

The present invention relates to improvements in sickle bar construction for mowing machines, and one object of the invention is to provide an improved sectional knife bar construction which will effect economy in repair cost by permitting the 10 renewal of defective or broken parts without incurring the delay, trouble and expense incident to repairing a continuous bar by the process of welding or the like.

To this end a novel sectional sickle bar 20 construction has been devised, with the parts so arranged that on the appearance of a fracture or other defect, the defective part may be quickly removed and a new part placed in position with but very little delay.

It is a further object to provide a neat, 25 simple and compact construction for the desired purpose, and of an inexpensive nature and requiring no change in the remaining portions of the machine.

With these general objects in view, the invention will now be described with reference to the accompanying drawing illustrating one form of construction which has been devised for embodying the improvements, 30 after which those features and combinations deemed to be novel will be severally set forth and defined in the appended claim.

In the drawing—

Figure 1 is a plan view, partly broken 40 away, illustrating a sickle bar constructed in accordance with the present invention;

Fig. 2 is an edge view of the same;

Fig. 3 is an edge view of a portion of the sickle bar on a larger scale;

Fig. 4 is a plan view of the lower face of the same portion of the bar; and

Fig. 5 is a transverse sectional view of the sickle bar.

Referring to the drawing in detail, this 50 illustrates the improvements as embodied in a sickle bar comprising the series of bar sections 2 arranged in alinement and in abutting relation, the combined length of the sections being that required to accommodate the desired number of knife blades

4, which blades are also arranged in alinement and abutting in the usual manner, but with each blade positioned to overlap a pair of the bar sections 2. In this position, each blade is adapted to be utilized to form a 60 joint with the corresponding bar sections, and suitable fastening means, as the rivets 6, are employed for uniting the parts in this relation.

For further securing the parts together 65 in rigid form, a series of plate members 8 may be applied to each joint on the under faces of the bar sections and the intermediate rivets 6 of the corresponding knife blades used for fastening said plate members 70 in position as illustrated. These intermediate pairs of rivets 6 may be countersunk if desired, and preferably are so countersunk with reference to the plate members 8 and the latter beveled as shown, so 75 that when the sickle bar is assembled in operative position upon the finger bar 10, proper clearance will be afforded for accommodating the plate members 8 and their rivets within the channel 12 of the finger 80 guards 14.

At the head of the sickle bar the rivets 6 may be utilized also for securing the head member 16 to which the usual pitman connection is made for operating the cutter. 85

In case of a broken, worn, or defective part, all that is necessary is to remove the portion which requires to be repaired or renewed, and this may be accomplished by cutting the appropriate rivets and taking 90 out the part in question. The rivets may obviously be readily sheared by simply supporting the sectional bar and delivering a few sharp blows with a hammer upon the head of the blade that is secured by the particular rivets to be cut. The renewal or repair of parts may then be quickly made and the same riveted back in place in the relation shown and described. The expensive and troublesome task of removing a 95 number of knife blades for the purpose of welding a continuous cutter bar, when broken, is obviated, as well as the time required to take the bar to a shop for making a repair of that nature. With the improved sectional bar construction, any needed repairs may be quickly made and attended to right on the ground at a minimum of expense and trouble.

From the foregoing it will be apparent 110

that a neat, simple and efficient construction has been devised for fulfilling the objects of the invention, and while what is now deemed to constitute the preferred form 5 of embodiment of the invention has been described and illustrated, the right is reserved to such formal changes and modifications as may fairly fall within the scope of the following claim.

10 Claim:

A sectional sickle bar comprising a series

of alined bar sections having straight abutting ends, a series of knife blades arranged in alinement on top of said sections, with each knife blade overlapping a pair of said sections, a series of plates each arranged opposite one of the knife blades and overlapping a pair of said bar sections on the under face thereof, and rivets passed through said knife blades, bar sections and 15 plates for securing them together. 20

WILLIAM F. AIDLLOTTE.
